UNITED STATES PATENT OFFICE

RALPH H. CHURCHILL, OF CHICAGO, ILLINOIS

ADVERTISING DISPLAY BOARD

Application filed January 11, 1928. Serial No. 245,906.

This invention relates to advertising display devices and has for its object to provide an improved device adapted to incite the interest of an observer and cause further inquiry respecting the particular merchandise advertised. Another object is to provide the device with apparatus for manipulation by the observer tending to increase his interest and curiosity respecting the merchandise.

10 It consists in certain features and elements of construction herein shown and described, as indicated by the claims.

In the drawings:

Figure 1 is a face view of an advertising display board embodying the present invention.

Figure 2 is a vertical section taken as indicated at line 2—2 on Figure 1, with the upper portion of the receptacle broken away 20 to show the details of construction.

Figure 3 is a fragmentary detail perspective view of the rear of the device showing the supporting brace.

In the drawings, the advertising display board is shown as comprising a card or panel, 1, of sheet material, hinged along its lower edge to a rearwardly extending base or foot piece, 2, preferably a continuation of the card, 1. The card may be of any desirable outline its face being provided with suitable coloring and descriptive matter relating to the article to be merchandised. A detachably connectible bracing member, 3, is upwardly inclined to maintain the card in spaced relation to the base, 2, in substantially upright display position. The lower end of said brace is provided with a slot, 4, through which is removably inserted an upwardly extending tongue, 5, struck out of the base, 2, at the rear edge. The upper end of said brace is reduced in width to provide a lug or tongue, 6, bent along a line indicated at, 7, and extending substantially horizontally through a slot, 9, in the card, 1. The shoulders, 10, formed by the reduced tongue abut against the back side of card, 1, and determine the upstanding position of said card, which is slightly inclined.

The lug, 6, provides support and position 50 ing for the upper end of a transparent recep-

tacle, 12, herein shown as a cylindrical "test tube", extending substantially upright with its lower end fitting through an aperture, 13, adjacent the lower edge of card, 1, and resting upon the base, 2, as shown in Figure 2. The upper end of the "test tube" is provided with a plug, 14, in which is mounted a tubular member, 15, extending downwardly in the "test tube" and terminating with an open end (not shown) adjacent the lower end of said tube; the upper end of tube, 15, being provided with a compressible bulb, 16. The "test tube", 12, is filled with a liquid indicated at, 17, preferably colored to attract attention, or the liquid may contain particles of a solid substance in suspension, giving it a novel color effect. Thus by squeezing the bulb, the liquid in the "test tube" will be violently agitated with a swirling motion and will appear as an interesting spectacle to an ordinary observer. Of course when the bulb expands, it sucks itself and the tube, 15, full of the liquid, as shown in Figure 2, and when it is contracted or compressed it expels forcibly, this contained liquid resulting in the agitation of the liquid remaining in the "test tube" 12. It is preferably, though not essential, that tube, 15, be also transparent so that the colored liquid therein will be visible through both tubes, 12 and 15. To permit the expulsion and intake of atmosphere in the tube, 12, above the liquid, due to its rise and fall resulting from the operation of the bulb, I provide a groove, 18, along the periphery of the plug, 14, venting the tube, 12, to the atmosphere. 85

The present invention is intended to promote and instill in an observer of the display sufficient interest to cause inquiry as to the relation of the apparatus on the board to the merchandise advertised, which may be partially answered by printed matter on the card. The manipulation of the bulb may also be suggested by a printed instruction, requesting the observer to perform a certain act, 90 for example, as herein shown, "Squeeze bulb". It is apparent that after an observer carries out the suggestion, an interest is created which will result in further inquiry of the product merchandised. 95

I claim:

1. In an advertising display device, a panel, a transparent receptacle carried on the panel and having liquid therein, and a compressible bulb connected with the receptacle and conveniently disposed for compression by an observer to forcibly expel fluid into the liquid, thus causing violent agitation thereof for the purpose of increasing the observer's interest.
2. In an advertising display device, a support, a panel, a transparent receptacle carried on the panel and having liquid therein, a compressible bulb, and a tube having one end connected to the bulb and the other end immersed in the liquid, whereby the compressing of the bulb by an observer forcibly expels fluid into the liquid, causing violent agitation thereof for the purpose of increasing the observer's interest.
3. An advertising display device comprising a panel of sheet material, a foot piece extending rearwardly from the panel and a brace extending upwardly from the foot piece towards the rear side of the panel; a bottle or tube-like container disposed for display in front of the panel with its lower end extending through an aperture therein for concealment behind said panel, and a lug on the upper end of the brace extending through the panel to engage the upper portion of said container.
4. In an advertising display device a support, a transparent receptacle carried on the support and containing a liquid having finely divided bright solid particles in suspension, and means for agitating the liquid connected with the receptacle and including an actuating member prominently exposed on the support in position to be manipulated by an observer for agitating the liquid in the receptacle and thus increasing the observer's interest therein.

RALPH H. CHURCHILL.
